United States Patent Office.

MARY MERRILL, OF MARENGO, ILLINOIS.

Letters Patent No. 74,763, dated February 25, 1868.

IMPROVED KNIFE AND FORK-SCOURER.

The Schedule referred to in these Letters Patent and making part of the same.

TO ALL WHOM IT MAY CONCERN:

Be it known that I, MARY MERRILL, of Marengo, in the county of McHenry, and State of Illinois, have invented a new and improved Device for Scouring Knives, Forks, and other articles of table and general cutlery; and I do declare that the following is a full and exact description thereof, reference being had to the accompanying drawings, and to the letters of reference marked thereon.

Figure 1 is an exterior view.

Figure 2 is a sectional view through the centre.

Figure 3 is a view showing the sieves.

The nature of my invention consists in providing a box, A, made of tin, or other metal, about two inches long, round or oval in shape, and having its upper end covered by a lid or cover of the same material. There is also an inner box or casing, E, and between the two the scouring-material passes, through sieves a.b. The upper portion of the box is filled with water-lime, sand, brick-dust, or other material commonly used for scouring, which passes through the sieves, and is delivered from the bottom of the box by its motion when being used. A piece of rubber or cork, C, inserted at the bottom of the box, and extending a short distance below it, is used for scouring the knife or other article of cutlery, as more clearly shown by the drawing. The rubber or cork is made flat at one end, for scouring knives, and rounded at the other, for scouring forks and spoons. It is held in position by a rod, a, and may be reversed at pleasure, for the purposes named.

What I claim as my invention, and desire to secure by Letters Patent, is—

The combination of the box A, the inner casing E, the sieves B and C, and the cork or rubber D, as and for the purposes specified.

MARY MERRILL.
